(57) **CLAIM**

The ornamental design for a cornhole bag with truncated corners as shown and described.

DESCRIPTION

FIG. 1 is a top plan view showing the new, original, and ornamental design of a cornhole bag with truncated corners; FIG. 2 is a bottom plan view thereof;

FIG. 3 is a left elevation view thereof, the right elevation view being a mirror image;

FIG. 4 is a front elevation view thereof, the rear elevation view being a mirror image; and

FIG. 5 is a perspective view thereof.

The broken lines shown in the drawings depict stitching of the cornhole bag with truncated corners and form no art of the claimed design.
